UNITED STATES PATENT OFFICE.

GEORGE MORLOT, OF PATERSON, NEW JERSEY.

IMPROVEMENT IN MACHINES FOR WASHING AND BEATING SKEINS OR HANKS.

Specification forming part of Letters Patent No. **222,363**, dated December 9, 1879; application filed August 12, 1879.

To all whom it may concern:

Be it known that I, GEORGE MORLOT, of Paterson, in the county of Passaic and State of New Jersey, have invented a new and useful Improvement in Machines for Washing and Beating Silk, &c., in Skeins, of which the following is a specification.

Figure 1 is a top view of my improved machine. Fig. 2 is a longitudinal section of the same, taken through the broken line $x\ x$, Fig. 1. Fig. 3 is a cross-section of the same, taken through the line $y\ y$, Fig. 2. Fig. 4 is a detail side view of the device for holding the skeins. Fig. 5 is a detail sectional view of the water-induction pipe.

Similar letters of reference indicate corresponding parts.

The object of this invention is to furnish an improved machine for washing and beating silk and other threads and yarns when in the skein, which shall be simple in construction and convenient and effective in use, removing all loose fibers and foreign particles, and forcing the water into and through all parts of the thread.

The invention consists in the combination of the levers, the balancing-weights, the clamping-rollers, and the hinged and weighted beater-boards with the rock-shaft, the frame, and the box or trough, and in the combination of the two parallel pivoted bars, the connecting-rod, the cord, chain, or strap, and the double cam-pulley with the connecting-rod and crank-shaft, the rock-shaft, the weighted levers, and the clamping and feed rollers, as hereinafter fully described.

A represents the frame, in the lower part of which is formed a shallow box or trough, B, to receive the water. The ends of the box or trough B are extended up to the top of the frame A. To the middle parts of the ends of one side of the frame A are pivoted the lower ends of two upright bars, C, to the upper ends of which are pivoted the ends of a connecting-rod, D. To one of the bars C is pivoted the end of a connecting-rod, E, the other end of which is pivoted to a crank or crank-wheel attached to the shaft F. To the shaft F is attached a pulley, G, to receive the driving-belt. Several machines may be driven from the same shaft F.

To the upright bars C, at a little distance

from their upper ends, are attached the ends of a cord, chain, or open belt, H, which makes one or more turns around a double cam-pulley, I, and is attached to the said pulley at the end of its shortest radius. The double cam-pulley I is attached to the end of a rock-shaft, J, in such a position that the said shaft may move faster as it approaches each end of its stroke. The rock-shaft J works in bearings in the centers of the top side bars of the frame A, and to it, within the said frame, are attached the middle parts of two levers, K, to the upper ends of which are attached two weights, L.

In the lower parts of the weighted levers K are mounted the journals of two parallel rubber rollers, M, at such a distance apart as to clamp the skeins N between them and squeeze out the water. The journals of the lower roller M revolve in notches in the weighted lever K, where they are secured in place by pins, so that the said roller M can be readily detached for putting on and taking off the said skeins N. To the projecting end of one of the journals of the upper roller M is attached a small pulley, O, around which passes an endless band, P, which also passes around a small pulley, Q, placed upon the rock-shaft J. The pulley Q runs loose upon the shaft J, and with it is rigidly connected a ratchet-wheel, R, into the teeth of which meshes the pawl S, pivoted to the weighted lever K, so that the oscillations of the levers K may turn the upper roller M and feed the skeins N forward, squeezing out the water and causing them to be operated upon each time in a new place. The pawl S is made double, so that by turning it over on its pivot it may be made to feed the skeins in either direction.

If desired, a pulley, T, and a band may be used for feeding the skeins forward. One journal of the shaft J is made hollow, and with it is connected the end of a hose, U, leading to a vat or other water-supply.

With a hole in the side of the shaft J is connected the upper end of a pipe, V, which passes down along the outer side of the weighted lever-bar K, is bent inward at right angles, and extends to or nearly to the other weighted lever K. The horizontal arm of the pipe V is thus parallel with, and at a little distance below, the lower roller M, so that it passes through

the skeins N, and is perforated with numerous small holes, so as to discharge the water in numerous fine streams or jets into and through the threads. To the upper corners of the frame A are hinged the outer corners of two boards, W, which are supported in a slightly-inclined position by stops X attached to them, and which engage with the top side bars of the frame A.

Y are weights secured adjustably to the said boards, so that they may be moved out and in as may be required. With this construction, as the weighted lever K is oscillated the skeins N are struck against the lower sides of the beater-boards W with a movement very similar to hand-beating, and between the strokes are swept through the water in the trough or box B, and at the same time are constantly exposed to the jets of water from the perforated pipe V, and are constantly having the water squeezed into and through and out of them by the action of the rollers M, so that

they will be thoroughly washed, beaten, and cleaned in a very short time.

Having thus described my invention, I claim as new and desire to secure by Letters Patent—

1. The combination of the levers K, the balancing-weights L, the clamping-rollers M, and the hinged and weighted beater-boards W with the rock-shaft J, the frame A, and the box or trough B, substantially as herein shown and described.

2. The combination of the two parallel pivoted bars C, the connecting-rod D, the cord, chain, or strap H, and the double cam-pulley I with the connecting-rod and crank-shaft E F, the rock-shaft J, levers K, and the rollers M, substantially as herein shown and described.

GEORGE MORLOT.
